JOHN WESLEY MONTAGUE, OF WINNIPEG, MANITOBA, CANADA.

REPEATING RIFLE.

1,121,526.

Specification of Letters Patent. Patented Dec. 15, 1914.

Application filed August 23, 1910. Serial No. 578,507.

To all whom it may concern:

Be it known that I, JOHN W. MONTAGUE, a subject of the King of Great Britain, and a resident of Winnipeg, Manitoba, Dominion of Canada, have invented a new and Improved Repeating Rifle, of which the following is a full, clear, and exact description.

This invention relates to a new and improved repeating rifle, and particularly relates to improvements in the breech bolt action and the magazine carrier.

An object of this invention is to provide a rifle in which the breech bolt is rotated by the reciprocation of the sleeve, and thereby cocks the rifle hammer by a cam action, the cams interlocking after the cocking action has been completed, by a forward motion of the hammer holding the several parts rigid after the bolt is turned, until it is necessary for the bolt to turn back into its proper place.

A further object of this invention is to provide a magazine carrier in which the carrying or wing portion is set at an angle to the axis of the carrier and revolves around the same in that form to carry the cartridge at the proper angle so that it may be properly deposited in the chamber of the rifle barrel.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a vertical section through the rifle chamber, showing one form of my improvements; Fig. 2 is a vertical fragmentary section on the line 2—2 of Fig. 1, parts being removed for the sake of simplicity; Fig. 3 is a detached view of a modified form of magazine carrier; Fig. 4 is a vertical transverse section on the line 4—4 of Fig. 3; Fig. 5 is a detail section of the firing pin sleeve, showing its interlocking connection with the breech bolt; Fig. 6 is a fragmentary transverse section showing one form of means for connecting the draw bar with the bolt sleeve; Fig. 7 is a longitudinal vertical section through another form of rifle embodying my invention; Fig. 8 is a transverse section showing the action of the magazine carrier in removing the last cartridge;

Fig. 9 is a vertical section on the line 9—9 of Fig. 7; Fig. 10 is a vertical section on the line 10—10 of Fig. 7; Fig. 11 is a longitudinal section through another form of rifle embodying my invention, which may be designated as the "military type"; Fig. 12 is a vertical section on the line 12—12 of Fig. 11; Fig. 13 is a vertical section on the line 13—13 of Fig. 11; Fig. 14 is a vertical section on the line 14—14 of Fig. 11; Fig. 15 is a longitudinal vertical section through another rifle embodying still another form of my device, showing the breech open, with the cartridge ready to enter the rifle barrel; Fig. 16 is a vertical section on the line 16—16 of Fig. 15; Fig. 17 is a vertical section on the line 17—17 of Fig. 15; Fig. 18 is a fragmentary vertical section showing the manner of connecting the draw bar to the bolt sleeve; Fig. 19 is a horizontal detail section showing the lock for preventing the cartridges escaping from the magazine; Fig. 20 is a detached view of the slide for closing the opening in the receiver chamber; Fig. 21 is a fragmentary view illustrating one end of the breech bolt; and Fig. 22 is a detail front end view of the breech bolt.

It is to be noted that the various embodiments of my invention are the same or similar in principle, and in the various figures the same parts will be indicated by the same reference numerals, and such features as differ from each other will be set forth by supplementary explanation.

Referring more particularly to the separate parts, 1 indicates a barrel, which is secured in any suitable manner to a receiver 2, which is provided with a breech opening or well 3. Slidably mounted in the receiver 2, there is provided a breech bolt 4, which is provided with a longitudinally extending central opening 5. At the rear end of this opening, there is provided a firing pin sleeve 6, which is connected to the breech bolt 4, as will be seen more clearly by reference to Fig. 5, by having a pair of lugs 7, which are adapted to slide in longitudinally-extending grooves 8 and be secured to the breech bolt 4 by being rotated a fraction of a revolution, so that the lugs 7 will engage in transverse grooves 9. This sleeve 7 forms a bearing for a firing pin 10, which is slidably mounted therein and in the opening 5 in the breech bolt 4. The firing pin 10 is provided at its front end with a collar 11, between which and the sleeve 6 there is

located a main spring 12, which is adapted to actuate the firing pin 10 to strike one of the cartridges when in position. For this purpose, the firing pin 10 is provided at its forward end with a striker 13, which is adapted to pass through a converging opening 14 in the front end of the breech bolt 4. In front of this opening 14, the breech bolt 4 is provided on its face with a slight recess 15, which is adapted to hold a cartridge, indicated at 16, in position, so that it will not fall away from the extractor when being ejected, after firing. The rear end of the firing pin 10 extends through an opening in a hammer 17, and in order to prevent rotation relative to said hammer and the remaining parts, the firing pin 10 is provided with a flattened portion at 18. For the purpose of securing the hammer and firing pin together, and in fact, securing all of the firing mechanism in the receiver, there is provided a nut 19, which has a screw-threaded opening, which engages a screw-threaded shank 20 on the firing pin 10. This nut is normally secured against rotation, as will be seen by reference to Fig. 1, by means of a latch 21, which is urged outwardly by a spring 22, so that the latch 21 will engage in a notch in the nut 19, and thereby prevent it becoming accidentally detached. When it is desired to remove the nut 19 for the purpose of taking the mechanism apart, it is merely necessary to depress the latch 21 from engagement with the notch in the nut, thereby permitting the nut to rotate by a slight manipulation with the fingers. The front face of the hammer 17 is provided with a pair of cams 23, which are adapted to engage similar cams 24 on the rear end of the breech bolt 4. The purpose of these cams is for cocking the rifle in a manner to be described hereinafter. The hammer 17 may be provided with suitable safety locks indicated by the numerals 25 and 26, which are adapted to coöperate with a spring pressed stop 27 on the stock 28 of the rifle. These elements, however, do not form a part of the present invention, and therefore will not be specifically described. The front end of the breech bolt 4 is provided with lugs 29, which are adapted to engage in cross cam grooves 30 in the receiver 2 when the breech bolt is in its forward or closed position, so as to lock the mechanism in the closed position, and prevent the breech bolt jarring open when a cartridge is discharged. These cross grooves form continuations of ways 90, in which the lugs are adapted to travel during the back and forth motion of the bolt. The outside of the breech bolt 4 is formed with a plurality of threads 31 and spaces 32, in this case six in number. These threads have a pitch of one turn in four and a half inches, and are shown as left-handed threads.

Concentrically mounted on the breech bolt 4, there is provided a breech bolt sleeve 33, which has similar threads and spaces to engage the threads and spaces 31 and 32. As will be seen by reference to the transverse sections, this sleeve 33 is provided adjacent its upper side with a lug 34, which extends the full length thereof, and slides in a groove 35 located in the receiver 2. There is also located on the sleeve 33, adjacent its lower side, a lug 36, which also extends the full length thereof and engages in a corresponding groove in the receiver 2. This structure prevents the sleeve from rotating; therefore, when the sleeve is reciprocated, it must cause the bolt to rotate by reason of the worm or screw-threaded connection therebetween. The sleeve may be operated in any suitable manner, and a number of ways of manipulating the same have been shown.

In the forms illustrated in Figs. 7, 9, 15, 16, 17 and 18, the sleeve 33 is shown as having an extension 37 formed on the lower lug 36, to which is secured in any suitable manner, as by means of interlocking lugs and recesses 38, a draw bar 39, the latter extending forward, where it may be operated in any suitable manner, as by means of a hand grip slidingly mounted on the barrel.

In the form illustrated in Figs. 11 and 14, commonly known as the "military type", a handle 40 is provided adjacent the side of the breech, which is connected to the sleeve, at the upper side thereof, as at the lug 34.

Still another form of connection for manipulating the sleeve is shown in Figs. 1 and 6, where the draw bar 39 is connected to an overhang 41, formed on the lug 34.

The upper lug 34 on the sleeve 33 is provided with a groove, in which is slidably mounted an extractor 42. This extractor may be connected to the breech bolt 4 by means of a lug 43, which is adapted to be sprung into a groove in the breech bolt after the extractor has been passed into the groove in the lug 34. In Fig. 15, this lug 43 is shown in the form of a double cross member. In Fig. 1, an additional lug 44 is used, for the purpose of forming a strong connection between the breech bolt and the receiver, to prevent accidental disengagement of the two parts when used in rifles firing heavily-charged cartridges. The lower lug 36 on the breech bolt sleeve 33 is also provided with a groove, in which is slidably mounted a bearing member 45, which is also connected by a tongue 46 to the breech bolt 4 by being sprung into a groove therein.

The purpose of this bearing member 45 is to offer a smooth surface to the uppermost cartridge in the magazine. The forward movement of the sleeve 33 is limited by the breech bolt itself, which is enlarged so as to have its upper surface extend flush with

opposite end to the wing. This will permit the wing to urge the forward end of the cartridge up, so that the cartridge will be in an inclined position when the breech bolt 5 is shifted to its open position, thereby adapting the cartridge to readily enter the barrel when the breech bolt is shifted forward, and still permitting the uppermost cartridge to have its front end depressed back into the 10 magazine when the breech bolt and the parts connected thereto are shifted to their closed position.

In the form illustrated in Figs. 1 and 2, the body portion of the carrier is disclosed 15 as comprising two parts 67 and 68, movable relative to each other on the pin bolt 54, and each having an individual spring 69, which is capable of rotating its part of the body portion relative to the other part.

20 Extending from the parts 67 and 68, there are provided arms 70 and 71, which are connected to opposite ends of a wing 72. This serves the same purpose as the form shown in Figs. 3 and 4, in that it permits 25 the front end of the uppermost cartridge to be projected, when desired, into the breech well, and to be depressed by the sleeve and sleeve bolt passing thereover. It will be noted by reference to Fig. 2 that the wing 30 in this case is shown as pivoted to the arms 70 and 71 and extending a considerable distance therefrom. Such a structure is desirable when the magazine 51 is to be located a considerable distance below the breech 35 well 3. The carrier body where the cartridges rest upon it is formed with a circumferential concavity at 73 so as to conform to the shape of the cartridges as they lie within such concavity at an angle to the axis of the 40 carrier. More specifically, for instance, if the main part of the cartridge is cylindrical, the concavity will be substantially elliptical in longitudinal section, the form corresponding to the shape of a cylinder cut by a plane 45 at an angle to its axis. By this construction the cartridges all rest on the carrier body substantially throughout their length. It will also be noted in the form illustrated in Fig. 1 that the magazine 51 tapers from its 50 rear to its front, so as to conform to the taper of the cartridge.

The forms illustrated are shown as adapted to tapering cartridges having non-projecting rims. Other forms may be utilized 55 for the purpose of manipulating cartridges with projecting rims, and in such an event, allowance will be made for the proper passage of each cartridge from the chamber to the breech well.

60 In order that the cartridges, when shifted from the magazine 51 to the breech well 3 may not be bodily projected into the air, there is provided a movable lip or stop 74, which extends laterally into the well chamber 65 through a groove in the receiver, and is piv-

otally connected at 75 to the receiver, and normally held in its inwardly-projecting position by means of a spring 76. This stop is substantially straight and extends longitudinally practically parallel with the axis 70 of the magazine. If it should be desired to remove the cartridges from the magazine chamber, without danger of exploding the same, it is merely necessary to depress the opposite end of the stop 74 against the tension of the spring 76, thereby removing the projecting portion from engagement with the outermost cartridge, and invert the rifle, so that the cartridges can drop into the hand held below the well opening. 75

The operation of the device will be readily understood when taken in connection with the above description. If we suppose the gun to be closed, and the breech bolt sleeve at the forward end of the breech 80 bolt, in order to open the gun it is necessary to draw back the sleeve, and in doing so the sleeve moves over the bolt one and one-half inches, or one-third the pitch of the worm thread on its inside, and thus turns the bolt 90 a full one-third of a revolution, which action presents the lugs of the bolt in line with the ways of the receiver, and also in line with the ribs on the outside of the breech bolt sleeve. While this turning action of the 95 breech bolt is taking place, the cams on the rear end of the bolt and the front end of the hammer have acted and compressed the hammer back three-fifths of its stroke, or about three-eighths of an inch. During the 100 last one-sixteenth of an inch of the turn of the bolt, the points of the two cams pass each other, and a reverse motion of the hammer of one-sixteenth of an inch takes place, forming an interlocking of the cams. This 105 back action of the cams is cut at about the same angle as the forward angle of the cam. This one-sixteenth of an inch of back action of the cams throws the bolt clean over to its full stroke, by means of the main spring 110 12 pulling the two sets of cams together. The interlocking of the cams holds the breech bolt sleeve and the hammer rigidly together 115 in one solid piece during the balance of the backward stroke, or until they have reached the breech bolt check, and the cartridge is raised out of the magazine in front of the bolt, ready to be carried forward into the rifle barrel. In whichever form of magazine carrier is used, the cartridge is automatically swung up into position by the spring shifting the wing around a part of a revolution. By pressing forward on the sleeve, the breech bolt passes forward with it as one piece, carrying the cartridge in 120 front of it into the chamber of the rifle, until the hammer reaches the sear 49. The hammer now stands still while the sleeve and bolt bear forward, and the lugs 29 on the bolt arrive at the cross grooves which 125 130

the outer surface of the sleeve. The rearward movement of the sleeve 33 is limited by the hammer 17 and also by a block on the extractor 42 provided at its rearward end and projecting inwardly sufficiently to engage the rear end of the sleeve 33 when the latter is in its rearmost position. The rearward movement of the bolt 4 is limited by a stop 91, which projects into the receiver in a manner which will be more clearly seen by reference to Fig. 12. The forward end of the extractor 42 is provided with a downwardly-extending tongue 47, which projects over the recess 15, and is adapted to engage on its upper surface the rim of the cartridge, so as to extract the same from the barrel 1. The work of the extractor may be aided by a spring-pressed pin 48, illustrated in Fig. 1, which engages the rear end of the cartridge, on the lower side thereof. For the purpose of holding the hammer 17 and permitting the forward movement of the breech bolt relative thereto, there is provided a sear 49, which is adapted to be released for the purpose of firing, by means of a trigger 50, when not prevented by the safety stop 27.

Disposed below the well 3; that is to say, subjacent the cavity located to the rear of the barrel 1, there is provided a magazine 51, in which the cartridges to be successively supplied to the barrel 1, are stored. For the purpose of automatically supplying the successive cartridges to the breech bolt, so that it can force them into the chamber in the barrel 1, I have shown several forms of magazine carrier. The main idea in all of these forms, however, is to provide a carrier with a wing portion which engages the cartridges, extending at an angle to the axis of rotation of the carrier, so as to allow for the taper in the cartridge, and said wing portion being convexed on the surface which engages the cartridge, so as to simulate a cartridge, and thereby offer the last cartridge to the breech bolt action in substantially the same position as it would be offered by one or more cartridges in front of the carrier.

In the forms illustrated in Figs. 7, 8, 9, 11, 14, 15, 16, and 17, there is shown in the magazine 51, a carrier 52, which is rotatably supported on a pin bolt 54. This pin bolt, with the carrier thereon, may, as in the form illustrated in Figs. 7, 8, 9, 15, 16 and 17, be inserted from the side, by removing a sliding plate 55 (most clearly seen in Figs. 9, 16 and 20), and sliding the flattened heads of the pin bolt 54 in grooves 56 (more clearly shown in Fig. 9) or, as in the case of the form shown in Figs. 11 and 14, the carrier may be passed through an opening formed by a hinged door 57 and secured in place by inserting the pin bolt 54 through the stock of the rifle in the form of a bolt.

The latter form is used when great strength is desired. In each of these forms, however, there is provided a spring 58, which is secured at one end to the stationary pivot pin bolt 54, and at the opposite end to the carrier 52, so that when the spring is coiled under tension, it will automatically tend to uncoil, and revolve with it the carrier, thereby forcing the cartridges before it.

In each form, the carrier comprises a body portion and a straight rigid wing. The wing may be integral with the body portion, as indicated by the numeral 60 in Figs. 8, 9, 14, 16 and 17. In such an event, the wing is secured rigidly to the body portion at an inclination corresponding to the amount which it is desired to elevate the front end of the cartridge, in transferring it from the magazine to the breech well. In other words, the wing in all forms of my invention is arranged at considerable angle to a plane intersecting it and passing through or coinciding with the axis of rotation of the carrier, whereby, as indicated in Figs. 14, 16 and 17, the cartridges are all disposed around said axis, each with its front or bullet end well in advance of the rear end, and as a result of this spiral disposition of the series of cartridges, each cartridge as it reaches the stationary lip adjacent the receiver will have its bullet end well elevated toward the axis of the gun bore, such action being due to the effect of the advanced bullet end of the next cartridge passing beneath the same, see Fig. 15, which it will be noted indicates the position of the cartridge immediately after the breech bolt has been retracted. In other words, the bullet end is being automatically elevated, by virtue of the spring 58 and form of the carrier, during practically the whole time the breech bolt is being retracted. For these reasons, therefore, my magazine structure is capable of such rapid operation as to adapt it for use in automatic firearms, a fact not heretofore possible with any other design of cylindrical magazines of which I am aware. The form and arrangement of the wing are such that the last cartridge in the magazine will be acted upon in substantially the same way as any other cartridge will be affected by the next succeeding cartridge, as above set forth.

In the form shown in Figs. 3 and 4, the wing, indicated at 61, is disclosed as being pivotally connected at one end to the body of the carrier, by means of a pin 63, and adjustably connected at the other end by means of a pin 64, which engages a slot 65 in the wing.

For the purpose of normally urging the movable end of the wing to its greatest inclination with the axis of rotation of the carrier 52, there is provided a spring 66, mounted on the pin 63 and secured at one end to the body of the carrier, and at the

are cut in the receiver to receive them. By continuing the pressure on the sleeve, the bolt commences to turn in this position, and the cams draw it away from the hammer 5 and finish the cocking of the rifle. This front camming action takes place during one-half of the stroke of the sleeve over the bolt, or while the sleeve travels three-quarters of an inch. The lugs have now arrived 10 at the dead cross face at a right angle to the axis of the rifle, and during the last one-half of the forward motion of the sleeve, the lugs are turned in until their full face rests on the faces of the grooves cut for them in 15 the receiver. It will thus be seen that there is no possible chance of the breech bolt being opened by the pressure of an explosion in front of it when the gun is fired. The front cross grooves which the bolt lugs 20 enter have a draw of one-quarter of an inch during the one-sixth of a revolution of the bolt, or about one-quarter of an inch while the bolt turns about three-eighths of an inch, allowing the breech bolt to force the cartridge 25 into the chamber.

It will be noted that the sleeve 33 closes over the cams when in its rearmost position to prevent dust, dirt, etc., from entering and clogging the mechanism. It will be further 30 noted that the extractor 42 covers the sleeve, bolt and cams, thereby keeping the screw threads on the sleeve and bolt, and the cams, free from foreign particles.

While I have shown several embodiments 35 of my invention, I do not wish to be limited to the specific details thereof, but desire to be protected in various changes, modifications and alterations which may come within the scope of the appended claims. It is 40 to be understood, furthermore, that the foregoing references to specific dimensions are to be interpreted as illustrations only, by way of comparison, and I do not intend them to be limitations, reserving the right 45 to construct the several parts of any suitable sizes or relative proportions.

Having thus described my invention, I claim as new and desire to secure by Letters Patent:—

50 1. The combination with a magazine, of a cartridge carrier mounted in said magazine and comprising a body portion formed in two parts movable relatively to each other, a wing secured at each end to said 55 parts, and an individual spring for rotating each of said parts.

2. The combination with a receiver, of a sleeve mounted in said receiver, said receiver having longitudinally-extending grooves 60 therein, said sleeve having lugs thereon, adapted to engage said grooves, said lugs having slots therein, a bearing plate located in one of said slots in one of said lugs, a breech bolt mounted within said sleeve, and

an extractor slidably mounted in the other 65 of said slots in the other of said lugs.

3. The combination with a receiver, of a sleeve slidably mounted in said receiver, a breech bolt mounted in said sleeve, a firing-pin sleeve mounted in said breech bolt and 70 having lugs on its forward end, engaging said breech bolt so as to prevent the rearward motion of said sleeve relative to said breech bolt, a firing pin slidably mounted in said sleeve, a hammer connected to said 75 firing pin, a cam on said breech bolt, and a cam on said hammer adapted to coöperate with said cam on said breech bolt to separate said hammer and said breech bolt, said last-mentioned cam being spaced apart from 80 said firing pin to form a cavity, into which said firing pin sleeve may pass.

4. The combination with a receiver, of a sleeve mounted in said receiver, said receiver having longitudinally-extending 85 grooves therein, said sleeve having lugs thereon adapted to engage said grooves, said lugs having slots therein, a bearing plate located in one of said slots in one of said lugs, a breech bolt within said sleeve, said breech 90 bolt having a screw threaded connection with said sleeve, an extractor slidably mounted in the other of said slots in the other of said lugs, a hammer, spring connections between said hammer and said bolt, 95 whereby said hammer and said bolt are normally urged toward each other, coöperating cams on said hammer and said bolt, for forcing said hammer and said bolt apart when said sleeve is moved in said receiver, and 100 means for locking said hammer and said bolt in their separated positions.

5. The combination with a receiver, of a sleeve mounted in said receiver, said receiver having longitudinally-extending grooves 105 therein, said sleeve having lugs thereon adapted to engage said grooves, said lugs having slots therein, a bearing plate located in one of said slots in one of said lugs, a breech bolt within said sleeve, said breech 110 bolt having a screw threaded connection with said sleeve, an extractor slidably mounted in the other of said slots in the other of said lugs and connected to the bolt, a hammer, spring connections between said 115 hammer and said bolt, whereby said hammer and said bolt are normally urged toward each other, coöperating cams on said hammer and said bolt, for forcing said hammer and said bolt apart when said sleeve is 120 moved in said receiver, means for locking said hammer and said bolt in their separated positions, means for limiting the motion of said bolt, and means for limiting the motion of said sleeve.

6. The combination with a receiver, of a breech bolt mounted in said receiver and having a plurality of threads on its outer

- surface, a sleeve, having a plurality of threads on its inner surface, mounted on said breech bolt, said receiver having longitudinally extending grooves there-
 5 in, said sleeve having lugs thereon adapted to engage said grooves to prevent the rotation of said sleeve, said lugs having slots therein, a bearing-plate located in one of said slots in one of said lugs, an extractor
 10 slidingly mounted in the other of said slots in the other of said lugs and connected to the bolt, a firing pin mounted in said breech bolt, a hammer connected to said firing pin, cams on said hammer and said breech bolt
 15 coöperating with each other to force said hammer and said breech bolt apart, and a spring connected to said firing pin and to said breech bolt and adapted to normally urge said hammer and said breech bolt toward each other, the limit of motion of said
 20 breech bolt and said sleeve and the pitch of said screw thread and said cams being such that the points of said cams will have slipped by each other before the complete
 25 travel in one direction of said sleeve, so that said breech bolt will be drawn toward said hammer for the remainder of the motion of said sleeve in the same direction, under the influence of said spring.
 30 7. The combination with a magazine, of a cartridge carrier rotatably mounted in said magazine, said cartridge carrier comprising a body portion and a straight rigid wing movably connected to said body portion and
 35 extending at an angle to the plane passing through the axis of the body portion, the connecting means for the wing providing for a variation in said angle during the rotation of the carrier.
 40 8. The combination with a magazine, of a cartridge carrier rotatably mounted in said magazine, said cartridge carrier comprising a body portion and a wing pivotally connected at its opposite ends to said body
 45 portion and extending at an angle to the axis of rotation of said cartridge carrier, and a spring for rotating said cartridge carrier.
 50 9. The combination with a magazine, of a cartridge carrier rotatably mounted in said magazine, said cartridge carrier comprising a body portion and a wing pivotally connected to said body portion on a substan-

tially longitudinal axis and extending at an angle to the axis of rotation of said cartridge carrier, and a spring for rotating said cartridge carrier.

10. The combination with a magazine, of a cartridge carrier rotatably mounted in said magazine, said cartridge carrier comprising a body portion and a wing connected to said body portion, such connection providing that the wing shall be capable of angular as well as circumferential movement with respect to the axis of the carrier. 65

11. The combination with a magazine, of a cartridge carrier rotatably mounted in said magazine, said cartridge carrier comprising a body portion and a wing connected to said body portion and extending at an angle to the axis of rotation of said cartridge carrier, whereby all the cartridges are carried around such axis with one end of each well in advance of the other, and means for permitting an angular motion of said wing relative to the axis of rotation of said cartridge carrier. 70

12. The combination with a magazine, of a cartridge carrier in said magazine, and means to rotate the cartridge carrier in the magazine, said cartridge carrier comprising a body portion having a circumferential elliptical concavity adjacent its rear end adapted to conform to the cylindrical part of a cartridge arranged therein at an angle 85 to the axis of the body portion, for the purpose set forth.

13. The combination with a magazine, of a cartridge carrier in said magazine, and means to rotate the cartridge carrier in the magazine, said cartridge carrier comprising a body portion having an elliptical concavity extending circumferentially around the rear end and a wing consisting of a straight rigid member pivotally connected to said body portion at an angle to a plane intersecting it and coinciding with the axis of the carrier, for the purpose set forth. 90

In testimony whereof I have signed my name to this specification in the presence of 100 two subscribing witnesses.

JOHN WESLEY MONTAGUE.
